UNITED STATES PATENT OFFICE

AXEL P. DE VEGA, OF BOSTON, MASSACHUSETTS

CIGARETTE PACK OPENER

Application filed January 16, 1929. Serial No. 332,950.

This invention relates to cigarette pack openers and has for its general object to provide a means of opening a package of cigarettes quickly and with a minimum of effort without injuring the contents.

A further object of the invention is to provide a device which will sever the end wrapping of a pack neatly and without causing small portions of the wrapper to be strewn about, which is the usual result when the pack is torn open in a haphazard fashion with the fingers.

Another object of the invention is to combine the utility of the device as a pack opener with that of an advertising medium.

A further object of the invention is to provide a device which is universal in its adaptation and which may be used for opening letters, as a finger nail cleaner or for various other purposes.

A further object of the invention is to provide a pack opener which may be secured to a fixed support at some convenient location as for instance upon or near a counter where cigarettes are vended.

Other objects and features will more fully appear from the accompanying specification in connection with the drawings and will be particularly pointed out in the claims.

In the drawings:

Fig. 1 is a plan view of a pack of cigarettes showing the relative position of the opener while severing the end of the wrapping from the pack.

Fig. 2 is a partial side elevation of a pack with the front wall of the pack broken away to show the opener in elevation in the same relative position as that shown in Fig. 1.

Fig. 3 is a front elevation of a different embodiment of the invention.

Fig. 4 is a perspective view illustrating the manner in which the device shown in Fig. 3 is used to open a package of cigarettes.

The device is chiefly adapted to opening cigarette packs but may be used for a number of other purposes. The device is extremely compact and for that reason may be readily carried about the person and if so carried is found useful for many things besides the opening of cigarette packs. For

instance it may be used as a letter opener or as a finger nail cleaner. The device may be constructed in various forms without departing from the invention. Aside from the portable type a useful form may be constructed which has means to attach it to a fixed support. Such a device may be attached to a wall, a piece of furniture such as a smoking stand, easy chair or the like or in some convenient spot or at several points about a store selling cigarettes.

Most everybody who has entered a store and purchased a package of cigarettes has experienced the awkwardness in trying to open the pack by the ordinary method of breaking or tearing the top open with the fingers often resulting in broken nails not to mention the loss of time and irritation of temper. In using the opener this is all avoided. Furthermore the device will constitute a valuable asset in such a place of business. By placing one or more of the openers in convenient locations customers will appreciate the extra service thus rendered.

A preferred embodiment of the invention consists of a thin blade 1 of suitable material having a maximum width exceeding the thickness of a pack of cigarettes one end of which is V-shaped tapering to a point 2 at its extremity. If it be desired the tapering sides of the V may be beveled as at 3 to provide a keener edge with which to sever the end from the pack. The end 4 opposite the point 2 may be made of various shapes. As illustrated herein it is of circular form and is connected to the opposite end of the blade by a portion 5 which tapers in a direction opposite to that of the cutting edges 3 from the point of maximum width to meet the circular portion at points which span about one quarter of the circular end portion. The tapered portions may be pointed by edges which are straight or they may be irregular or curved without departing from the invention.

Desirably the V-shaped portion of the blade is considerably shorter than the width of a cigarette pack so that where only a portion of the top is to be opened the point 100

of the blade will not penetrate the side of the wrapper opposite to the side through which the point is inserted.

Another form of the invention is illustrated in Figs. 3 and 4 wherein the end of the blade opposite to the point or severing end is provided with a shank portion 6 which is bent back upon the blade so that it is spaced therefrom a distance substantially equal to the thickness of the end wrappings upon the pack. The shank portion 6 is provided with screw holes 7 by means of which the device may be attached to a fixed support. When so attached the device becomes a very convenient and efficient opener. If the support has a smooth flat surface it is necessary simply to slide the end face of the pack along the surface until the portion of the pack it is desired to open strikes the point of the opener then with a quick pull the pack is opened as much as desired. A short push or pull will open the corner exposing 4 or 5 cigarettes while a longer push or pull will cut the whole top leaving it attached only to one of the long sides. When using the opener thus it will be found that the flat surface of the support aids in guiding the pack which insures a straight even cut and prevents the blade from injuring the contents of the pack.

The invention may be made of any material suitable to the use to which it may be put. In the form illustrated in Figs. 3 and 4 it may be made of a metal in order to provide sufficient rigidity, such as brass, aluminum, copper, bronze or steel. Some of the above materials may also be used to make the portable opener shown in Figs. 1 and 2. However, in order to insure lightness the portable opener may be advantageously made of celluloid, fibre board or bakelite. In using the latter class of materials the device may be made attractive by adding a decorative effect of color. In the case of celluloid or bakelite a varigated translucent effect may be employed.

A valuable feature of the device is its adaptability to use as an advertising medium. The circular end section 4 may contain an advertising legend as shown in the drawings. The simplicity of the device adds to its effectiveness and durability and also reduces the cost of manufacture. Since the cost of manufacture is low the opener may be distributed freely as an advertising medium at small cost and in this manner educate more people to the real usefulness of the opener so that the demand will therefore be increased.

Having thus described the invention, what is claimed as new, and desired to be secured by Letters Patent, is:

1. A cigarette pack opener of the character described comprising a thin flat blade

of uniform thickness of a maximum width materially exceeding the thickness of a pack and converging at one end and of a length greater than the width of the package to provide a handle, operable to enter the pack between the ends of the cigarettes and the end of the enclosed wrapper and upon endwise movement selectively to cut a part or the whole of said end from the side walls of the wrapper.

2. A cigarette pack opener of the character described comprising a thin flat blade of a uniform thickness having a maximum width materially exceeding the thickness of a pack and converging to a point at one end and of a length greater than the width of the package, operable to enter the pack between the ends of the cigarettes and the end of the enclosed wrapper, and upon endwise movement selectively to cut a part or the whole of said end from the side walls of the wrapper.

3. A cigarette pack opener of the character described comprising a thin flat blade of uniform thickness and of a maximum width exceeding the thickness of a pack and V-shaped at one end and of a length greater than the width of the package whereby upon endwise movement the apex of the V will pierce the wrapper to permit the opener to enter between the ends of the cigarettes and the end portion of the wrapper to sever a part or the whole thereof from the side walls of the pack.

4. A cigarette pack opener of the character described comprising a thin flat blade of uniform thickness of a maximum width materially exceeding the thickness of a pack converging at one end to a point and having at its other end a handle disposed in the same plane as said blade having an area bearing advertising matter, operable upon endwise movement to pierce the wrapper to permit the opener to enter between the ends of the cigarettes and the end portion of the wrapper to sever a part or the whole thereof from the side walls of the pack.

5. A cigarette pack opener of the character described comprising a thin blade of a maximum width exceeding the thickness of a pack converging to a point at one end and having means adapted to secure it to a support whereby when the end face of the pack is moved along the surface of the support against said point the blade will enter between the ends of the cigarettes and the end portion of the wrapping and selectively sever a part or the whole thereof from the side walls of the pack.

6. A cigarette pack opener of the character described comprising a thin blade of a maximum width exceeding a thickness of a pack converging to a point at one end and having means adapted to secure it to a support to space it therefrom a distance sub-

stantially equal to the thickness of the end portion of the wrapping whereby when the end face of a pack has moved along the surface of the support against said point the 5 blade will enter between the ends of the cigarettes and the end portion of the wrapping to selectively sever a part or the whole thereof from the side walls of the pack.

In testimony whereof, I have signed my 10 name to this specification.
